UNITED STATES PATENT OFFICE.

HENRY C. FRECH, OF SAVANNAH, GEORGIA.

KEY RING.

Application filed February 19, 1923. Serial No. 619,917.

To all whom it may concern:

Be it known that I, HENRY CHARLES FRECH, a citizen of the United States, residing at Savannah, in the county of Chatham and State of Georgia, have invented certain new and useful Improvements in Key Rings, of which the following is a specification, reference being had to the accompanying drawings.

10 This invention relates to certain improvements in key rings and it is an object of the invention to provide a novel and improved device of this general character whereby the keys may be readily and conveniently engaged or disengaged.

Another object of the invention is to provide a novel and improved device of this general character having means whereby the same may be engaged with a belt, the 20 waist band of another garment or the like.

The invention consists in the details of construction and in the combination and arrangement of the several parts of my improved key ring whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:—

Figure 1 is a view in perspective illustrating a key ring constructed in accordance with an embodiment of my invention;

Figure 2 is a front elevational view, with 40 portions broken away of the device as herein disclosed;

Figure 3 is a side elevational view of the device as herein set forth with a portion of the annular member indicated in a second position by broken lines;

Figure 4 is a sectional view taken substantially on the line 4—4 of Figure 2; and

Figure 5 is a sectional view taken substantially on the line 5—5 of Figure 2.

50 As disclosed in the accompanying drawings, my improved key ring comprises an annular split member 1 preferably round in cross section. One end portion of the member 1 is provided with an outstanding 105 radially disposed flat extension or plate 2, said plate extending beyond said end of the

member 1 and having its inner portion cut away to receive the opposite end portion of the member 1.

Pivottally engaged to the opposite sides 60 of the extension or flat plate 2 and at a point adjacent the outer end thereof are the swinging plates 3 which when superimposed upon the extension or plate 2 are of a length to bridge the meeting ends of the 65 member 1 whereby the keys or the like engaged with said member 1 are held against displacement.

The plates 3 are maintained in locking position through the medium of the sliding sleeve or collar 4. This collar 4, when moved inwardly of the pivotal mounting for the plates 3, surrounds said plates 3 and the extension or plate 2 and thereby effectively hold the plates 3 in their locked 75 position.

The outer end of the extension or plate 2 is provided with an outstanding eye member 5 which is interlocked with the eye member 6 carried by an end portion of a 80 hook member H. The hook member H comprises the overlying arms 7 and 8 which are adapted to receive therebetween a belt, the waist band of another garment or the like whereby the key ring can be readily 85 and conveniently carried by a person.

The arm 7 of the hook member H is provided with the slot 9 while the inner or free end portion of the second arm 8 is provided with a returned finger 10 which 90 provides a head to facilitate the maintenance of the hook member H in applied position.

It is to be understood that the arm 8 possesses a certain degree of inherent resiliency to facilitate its application or removal and when the hook member H is engaged with a belt the returned finger 10 underlies the belt and thereby serves to prevent accidental displacement of the hook 100 member H therefrom.

From the foregoing description it is thought to be obvious that a key ring constructed in accordance with my invention is particularly well adapted for use by reason of the convenience and facility with which it may be assembled and operated, and it will also be obvious that my invention is susceptible of some change and modification without departing from the 110 principles and spirit thereof and for this reason I do not wish to be understood as

limiting myself to the precise arrangement and formation of the several parts herein shown in carrying out my invention in practice except as hereinafter claimed.

5 I claim:—

1. A key ring comprising a split member, an outstanding plate carried by the member adjacent to an end thereof, said plate having an end portion cut away to receive 10 the opposite end portion of the member, swinging plates carried by the opposite faces of the first named plate and adapted to overlie the meeting end portions of the member, and a slidable collar embracing 15 the first named plate and the swinging

plates, said collar when in one position holding the swinging plates against movement.

2. A key ring comprising a split member, an outstanding plate carried by the member adjacent to an end thereof, a 20 swinging plate carried by the first named plate and adapted to overlie the meeting end portions of the member, and a slidable collar embracing the first named plate and the swinging plate, said collar when in one 25 position holding the swinging plate against movement.

In testimony whereof I hereunto affix my signature.

HENRY C. FRECH.
